FIG. 1

FIG. 2

FIG. 3

FIG. 4

FIG. 5

FIG. 6

FIG. 7

FIG. 8

FIG. 1 is a front elevational view of a combined hand mounted rear view mirror and reflector showing my new design, it being understood that the strap has been omitted in FIGS. 2 thru 8 for convenience of illustration;

FIG. 2 is a rear elevational view thereof;

FIG. 3 is a bottom plan view thereof;

FIG. 4 is a side elevational view thereof;

FIG. 5 is a front elevational view of a combined hand mounted rear view mirror and reflector showing a second embodiment of my new design;

FIG. 6 is a rear elevational view of the embodiment shown in FIG. 5;

FIG. 7 is a front elevational view of a combined hand mounted rear view mirror and reflector showing a third embodiment of my new design; and

FIG. 8 is a rear elevational view of the embodiment shown in FIG. 7.

The pattern which has been fragmentarily shown on the reflector in FIGS. 2, 6 and 8 is understood to be repeated throughout the entire surface of said reflector.

I claim:

The ornamental design of a combined hand mounted rear view mirror and reflector, as shown and described.
